UNITED STATES PATENT OFFICE.

ELIJAH KING, OF SAMS, KENTUCKY, ASSIGNOR OF ONE-FOURTH TO
ACHILES KELLEY, OF PRYSE, KENTUCKY.

AUTOMATIC CAR-COUPING.

No. 821,505.

Specification of Letters Patent.

Patented May 22, 1906.

Application filed November 29, 1905. Serial No. 289,643.

To all whom it may concern:

Be it known that I, ELIJAH KING, a citizen of the United States, residing at Sams, in the county of Estill and State of Kentucky, have 5 invented certain new and useful Improvements in Automatic Car-Couplers; and I do hereby declare the following to be a full, clear, and exact description of the invention, such as will enable others skilled in the art to 10 which it appertains to make and use the same, reference being had to the accompanying drawings, and to the letters of reference marked thereon, which form a part of this specification.

15 This invention relates to new and useful improvements in automatic car-couplers; and the object of the invention is to produce a simple and efficient apparatus of this nature whereby cars may be conveniently uncoupled without the necessity of a person going between the cars and comprises a spring-actuated hook with lever mechanism for tilting the hook when it is desired to release the coupling by means of a rod connected to one end of the coupler-bar.

20 My invention comprises various details of construction and combinations and arrangements of parts, which will be hereinafter fully described and then specifically defined 25 in the appended claims.

I illustrate my invention in the accompanying drawings, in which—

Figure 1 is a top plan view of my improved coupler, showing the parts uncoupled; and Fig. 2 is a top plan view of one 35 of the couplers with the parts shown in position to uncouple.

Reference now being had to the details of the drawings by letter, A designates a platform which may be attached to the bottom 40 of a car in any suitable manner, and B designates a coupler-bar, having a hook B' at one end, and said coupler-bar is pivotally mounted upon a pin C, passing through a cross-piece D, which connects the side pieces F, rising from said platform, and a spring G is fixed at one end to one of said pieces F, and its free end bears against the inner end of the coupler-bar, the office of said spring being to 45 normally return the coupler-bar to a coupling position after said coupler-bar has been tilted to uncouple the car.

Pivotally connected to the inner end of the coupler-bar is a link K, which is connected

55 pivotally to one arm of an angle-lever N, which is mounted upon a pivotal pin O, passing through a cross-piece O' and said platform. An arm N' of said lever N is pivotally connected to a locking member J, which is adapted to be reciprocated as the angle-lever 60 is tilted and to be thrown intermediate the rear convexed edge of the coupler-bar and the adjacent strip F for the purpose of affording means whereby the coupler may be prevented from being accidentally tilted when 65 held in a coupled relation.

S designates a curved resilient bar, which is fastened to one end of a strip F and provided for the purpose of guiding and throwing the coupler-bar of an approaching car, so 70 that it will hook into the coupler-bar when they come together.

T designates a rod, the inner end of which is connected to an elongated eye T', fastened to the inner end of the coupler-bar B, and 75 passes through the side F, where its end is turned to form a handle T², whereby an operator by pulling upon said rod and against the tension of said spring G may cause the coupler-bar to tilt to effect an uncoupling 80 and at the same time to cause the angle-lever N to tilt and the locking member J to be withdrawn from its locking position intermediate the coupler-bar and the side F.

While I have shown a particular form of 85 apparatus illustrating the details of my invention, it will be understood that the same may be varied in different ways to adapt the invention to different conditions without in any way departing from the spirit of the in- 90 vention.

Having thus fully described my invention, what I claim as new, and desire to secure by Letters Patent, is—

1. In combination with a platform and 95 sides therefor, a tilting coupler-bar mounted intermediate said sides, a spring bearing against said coupler-bar, a pivotal angle-lever, a locking member pivoted to one of the arms of said angle-lever, and adapted to be 100 normally positioned intermediate said coupler-bar and one of said sides, a link connecting the other arm of said angle-lever with the coupling-bar, and a rod connected to said bar and passing through one of said sides, as set 105 forth.

2. In combination with a platform and sides therefor, a tilting coupler-bar mounted

intermediate said sides, a spring bearing against said coupler-bar, a pivotal angle-lever, a locking member pivoted to one of the arms of said angle-lever, and adapted to be normally positioned intermediate said coupler-bar and one of said sides, a link connecting the other arm of said angle-lever with the coupling-bar, a rod connected to said bar and passing through one of said sides, and a curved resilient bar fastened to one of said

sides and adapted to guide a coupling-bar as two cars come together to be coupled, as set forth.

In testimony whereof I hereunto affix my signature in the presence of two witnesses.

ELIJAH KING.
